A. J. GROSS.

FUSIBLE LINK.

APPLICATION FILED NOV. 2, 1914.

1,278,912.

Patented Sept. 17, 1918.

UNITED STATES PATENT OFFICE.

ALLAN J. GROSS, OF CHICAGO, ILLINOIS, ASSIGNOR OF TWO-THIRDS TO JOHN L. KENNEDY, OF CHICAGO, ILLINOIS.

FUSIBLE LINK.

1,278,912.

Specification of Letters Patent. Patented Sept. 17, 1918.

Application filed November 2, 1914. Serial No. 869,949.

To all whom it may concern:

Be it known that I, ALLAN J. GROSS, a citizen of the United States, residing at Chicago, in the county of Cook and State of Illinois, have invented certain new and useful Improvements in Fusible Links, of which the following is a description.

My invention relates to fusible links adapted for various uses, and particularly for holding devices under tension or pressure, but releasing the same upon the application of heat at a predetermined temperature. The device is applicable for many uses, as for example, for holding the sprinkler head parts of an automatic fire extinguishing system, to control the closing or breaking of an electrical circuit, sound an alarm, maintain windows, doors, etc., open or closed, and the like. It has among its objects the production of a device of the kind described that is simple, inexpensive, durable, attractive, efficient, and satisfactory, and which may be used wherever found applicable. It has among its further objects the production of a link of the kind described that will be extremely strong and rigid and stand a considerable strain, and yet readily respond and release at a predetermined temperature.

To this end my invention consists in the novel construction, arrangement and combination of parts herein shown and described, and more particularly pointed out in the claims.

In the drawings, wherein like reference characters indicate like or corresponding parts,

Figure 1 is a side elevation of one side of the link;

Fig. 2 is a similar view of the opposite side;

Fig. 3 is a sectional view taken substantially on line 3—3 of Fig. 1;

Fig. 4 is a sectional view taken substantially on line 4—4 of Fig. 3;

Fig. 5 is a perspective view of a portion of the link;

Fig. 6 is a sectional view similar to a portion of Fig. 3, showing a slightly different construction, and

Fig. 7 is a detail view illustrating a slightly modified construction of one of the parts.

In the drawings I have shown a link particularly adapted for use on sprinkler heads in automatic fire extinguishing systems, the

link being considerably enlarged, however, for the purpose of clearly showing the details of the construction. The size of the link depends upon the particular use for which it is intended, the operation being the same regardless of the size. The preferred form of link consists of a substantially stirrup-shaped member 1, a coöperating recessed part 6, a closing or retaining member 14, suitable means arranged within the parts 1 and 6 together with the fusible means arranged to detachably secure the parts mentioned together. The stirrup-shaped member 1 is provided with extending parts or legs 2, which as shown particularly in Figs. 1 and 3, are integrally connected at the base by a connecting part 3, which connecting part forms a shoulder or abutment 5. As will be hereafter referred to, the ends 75 need not be integrally connected, and in that case the link part might more properly be termed U-shaped, although substantially stirrup or U-shaped is applicable as descriptive for either form. The coöperating 80 link part 6 is of suitable shape and size and offset as at 7, forming a recess 8. It will be noted by referring to Fig. 3, that the edge or face 9 of the offset is within the face of part 6, or that is the offset is slightly less 85 than the thickness of the material. While in the drawing an opening is shown at the top of the offset, the material ordinarily yields or stretches enough so that the opening is very small, if any at all. At the end 90 of part 6 within the stirrup is provided a notch 10, the purpose of which will be more fully explained hereafter. The stirrup-shaped part is offset between the ends, as for example at 4, so that the end of the stirrup-shaped part is in the plane of the part 6 when the parts are operatively positioned and secured together face to face, as shown.

Arranged within the parts, as shown in Figs. 3 and 4, is the means for engaging the shoulder 5 of one part and the shoulder at 8 in part 6. For this purpose I have shown two cylindrical rolls 11 and 12, which are preferably made of a diameter so as not to extend beyond the outer faces of legs 2 of 105 the link part 1 when positioned as shown. About the parts is arranged a plate 14, preferably flanged at the ends as at 15. This may be secured in position in any suitable way, as for example, by soldering, as at 17, 110

or in an equivalent manner. (See Figs. 2 and 4). Also fusible material is sweated or poured into the spaces between the rolls, or in the chamber formed by the parts, which 5 solidifies and also tends to maintain the parts together. The face of plate 14 affords a convenient space to place information concerning the link, for example as indicated in Fig. 1.

10 The centers of the rolls 11 and 12, that is the longitudinal axis of each, are slightly past the divisional line between parts 2 and 6, and within parts 2, owing to the fact that the offset 7 is offset less than the thickness 15 of the material of part 6. In the form shown in Fig. 6, the link parts 2, 6 and 14 are similar to those previously described, except a block 20 is employed in place of the two rolls 11 and 12.

20 I have shown in Fig. 2, in dotted, two of the sprinkler head arms or members 18 and 19, which extend through the opening between the links and engage part 1 and part 2. The link holds these parts together 25 and prevents their separation. When, however, heat reaches the link and the temperature is sufficient to fuse the fusible soldering metal 16 and 17, the link yields so that the arms or parts 18 and 19, which are under 30 tension and hold the valve shut, quickly separate. Owing to the rolls 11 and 12 being slightly off center, the same tend to throw the link parts apart. The same is true with the block 20. The solder or fusible material 35 are, of course, of suitable composition to melt at the desired temperature.

I have not considered it necessary to illustrate in detail a sprinkler head, or other device, secured or controlled by the link. It 40 might be mentioned that in use the link is preferably inverted with the part 6 at the top. The purpose of this is that the water seat of the sprinkler head being below the link (as well known to those familiar with 45 the art) there is less danger of the water striking the link when the valve first opens. The form of parts 1, 6 and 14, may, of course, be modified in shape, but the design shown is particularly desirable, as it is economical 50 to manufacture, of light weight and yet strong. It will be noted that the form shown in some ways resembles a small padlock, and as such is somewhat ornamental.

A slight variation in the construction is 55 shown in Fig. 7, in which 2'-2' represent the legs of the U or sides of the stirrup. In this construction, however, the legs are disconnected at the ends, although formed with shoulders 3', the central portion of the connecting part being cut away. Enough is cut 60 away so that the sprinkler parts or toggle levers will clear the opening. It will be noted by referring to the figure that the sides 3' are slightly inclined or cut at an angle, and the shoulders need only be large

enough to engage the ends of and coöperate with the roller 11, or its equivalent. With this construction the rollers prevent the legs from being forced together, while the band or covering member 14 prevents their separation. When this link is in use and in inverted position, upon fusing of the solder the part will release, and there can be no possible chance for this link part to catch and be suspended by the parts of the sprinkler head. Among the many advantages of the particular type of construction shown, in which the coöperating mechanism is at one side of the fusible material, it may be mentioned that the fusible material may be 70 placed at any distance from the coöperating mechanism by lengthening or shortening the parts, so that, as previously set forth, the same may be arranged at a point where there is no possible chance of water striking the 75 link and cooling it when the valve is open; the parts 18 and 19 constituting the coöperating mechanism (shown in dotted) may be arranged very close together; the soldering areas may be increased to any desired 80 extent; inspection of the fusible retainer may be conveniently made; and further this arrangement permits a construction substantially as shown in Fig. 7, the advantages 85 of which have been mentioned before.

Having thus described my invention, it is obvious that various immaterial modifications may be made in the same without departing from the spirit of my invention; hence I do not wish to be understood as limiting myself as to the exact form, construction, arrangement and combination of parts 90 herein shown and described, or uses mentioned.

What I claim as new and desire to secure 105 by Letters Patent is:—

1. A fusible link, comprising two complementary members arranged face to face, means arranged within the confines of said members at the adjacent ends for normally 110 positively preventing relative movement of said members, and means for detachably securing said part together, said members arranged to coöperate at one side of said first mentioned means for engagement with suitable parts of a coöperating mechanism.

2. A fusible link, comprising a stirrup member, a shorter coöperating face member adapted to be positioned against the face of said first member with one of its 120 ends adjacent the end of the stirrup member, and provided with a recess formed therein, in combination with a closure member adapted to close the opposite face of the stirrup member and embrace the side 125 edges thereof, the three members forming a chamber, said stirrup member and coöperating member arranged to engage the coöperating mechanism at one side of said recess, in combination with coöperating 130

mechanism positioned in the chamber, and fusible means for holding said parts together, said mechanism arranged to forcibly separate the several members when released 5 from the retaining fusible means holding them together.

3. A fusible link, comprising a stirrup member, a coöperating member adapted to be positioned against the face of the stirrup 10 near one end thereof, said stirrup member being bent at the free end to bring the same substantially in line with said coöperating member when so positioned, said coöperating member being formed with a recess and

15 a closing wall for one side thereof, and a closing member for the other side of the recess, comprising a suitably shaped member closing the opposite face of the recess and embracing the edges of the stirrup, in combination with separate means positioned in the recess, and arranged to forcibly separate said several parts when released from the effect of the solder holding them together.

25 4. A fusible link, comprising a stirrup member, a coöperating member adapted to be positioned against the face of the stirrup near one end thereof, said stirrup member being bent at the other end to bring the

30 same substantially in line with said coöperating member when so positioned, said coöperating member being formed with a recess and a closing wall for one side thereof, and a closing member for the other side of

35 the recess, comprising a suitably shaped member closing the opposite face of the recess and embracing the edges of the stirrup, in combination with superimposed rollers positioned in the recess and closely

40 filling the same, arranged to positively separate the parts when freed from the influence of the solder holding them together.

5. A fusible link, comprising a stirrup member, a coöperating member, adapted to

45 be positioned against the face of the stirrup near one end thereof, said stirrup member being bent at the free end to bring the same substantially in line with said coöperating member when so positioned, said coöperating member being formed with a recess and a closing wall for one side thereof, and a closing member for the other side of the recess, comprising a suitably shaped member closing the opposite face of the recess

55 and embracing the edges of the stirrup, in combination with superimposed rollers positioned in and closely fitting the recess, with their centers offset from the line of contact of the stirrup and the recess closure

60 member, whereby the parts will be positively separated when freed from the effect of the soldering.

6. A fusible link, comprising a stirrup member, a coöperating member adapted to

65 be positioned against the face of the stirrup

member at one end thereof, said stirrup member offset intermediate the ends a distance to bring the other end in the plane of said coöperating member when positioned, said coöperating member formed with a recess in the face adjacent the face of the stirrup member, a closing member positioned on the opposite face of the stirrup member with the ends bent to embrace the edges of the stirrup and coöperating member, retaining means arranged within said recess and stirrup member and engaging both parts, and fusible means for securing the several parts together.

7. A fusible link for sprinkler heads, comprising a stirrup-shaped member arranged at one end for engagement with a coöperating part of the sprinkler mechanism, a coöperating member adapted to be positioned against the face of the stirrup member at one end thereof, said stirrup member offset intermediate the ends a distance to bring the end in the plane of said coöperating member, said coöperating member formed with a recess in the face adjacent the face of the stirrup member, a closing member positioned on the opposite face of the stirrup member with the ends bent to embrace the edges of the stirrup and coöperating member, retaining means arranged within said recess and stirrup member, and engaging both parts, and fusible means for securing the several parts together.

8. A fusible link for sprinkler heads, comprising a stirrup-shaped member arranged at one end for engagement with a coöperating part of the sprinkler mechanism, a coöperating member adapted to be positioned against the face of the stirrup member near the opposite end thereof, and formed at its end adjacent said first mentioned end of the stirrup member to engage a coöperating part of the sprinkler mechanism, a U-shaped member positioned on the opposite side of the stirrup member from said coöperating member with the ends extending at the edges of said stirrup member and coöperating member, and of sufficient length to project slightly beyond the outside face of the coöperating member, said coöperating member provided with a recess therein, means arranged to engage the coöperating member at one end of said recess and the stirrup member adjacent the other end of said recess, and fusible means for securing the said parts together.

9. The combination in a fusible link, of a stirrup-shaped member, arranged at the end for engagement with a coöperating part, a coöperating member of less length than said stirrup member arranged at one end of the stirrup and provided with a recess in the inner side thereof, the end adjacent the first mentioned end of the stirrup member arranged for engagement with a coöperating

part, a closing member arranged on the other side of the stirrup member at said end with the end extended at the edges of said parts beyond the outer face of said coöperating member, superimposed rollers positioned within the confines of the stirrup and recess in said coöperating member with their centers offset from the line of contact of the stirrup and member, and fusible metal arranged within the recess and stirrup about said rollers, and at the ends of said closing member on the outer face of the coöperating member.

10. A fusible link, comprising the combination of a substantially U-shaped member formed with shoulders adjacent the ends of the legs, a coöperating member formed at its end to engage a coöperating part positioned between said end and the closed end of said 15 U-shaped member and with a shoulder therein, means for detachably securing said parts together, and means arranged between said shoulders for normally positively preventing the sliding of one part upon the other,

said first mentioned part offset intermediate 25 the ends so as to lie substantially in the plane of said second part.

11. The combination in a fusible link of two coöperating members, one shorter than the other and arranged face to face, with 30 one end of the longer member extending beyond the end of the other, said parts arranged to engage about coöperating mechanism between the extending end of the long part and the adjacent end of the other 35 part, and means at the other ends of said parts overlying each other at one side of the coöperating mechanism for normally maintaining said parts in operative relation and preventing the sliding of one over the 40 other.

In testimony whereof I have hereunto signed my name in the presence of two subscribing witnesses.
